ATTORNEY.S

UNITED STATES PATENT OFFICE

WILLIAM C. RITTER, OF DETROIT, MICHIGAN, ASSIGNOR TO LONG MANUFACTURING COMPANY, OF DETROIT, MICHIGAN, A CORPORATION OF MICHIGAN

RADIATOR ASSEMBLING APPARATUS

Application filed January 26, 1931. Serial No. 511,415.

This invention relates to improved method and apparatus for assembling heat exchange units of the fin and tube type.

One of the principal objects of this invention is to simplify the method of manufacture and reduce the cost thereof to a minimum by providing assembling apparatus designed to engage the marginal portions of the fins for rigidly holding the latter in proper and uniform spaced relation to each other while the tubes are assembled therewith.

With the foregoing as well as other objects in view, the invention resides in the novel construction of the apparatus and the simplicity of the method which will be more fully hereinafter set forth, especially when considered in connection with the accompanying drawings, wherein:

Figure 1 is a perspective view of my improved apparatus having certain parts broken away for the sake of clearness;

Figure 2 is a fragmentary plan view of the construction shown in Figure 1; and

Figure 3 is a cross sectional view through the construction illustrated in Figure 1.

The apparatus illustrated herein for carrying out the method to be presently described is extremely simple in construction and as shown in Figure 1 comprises a box-like construction 10 having top, bottom, end and side walls 11, 12, 13 and 14, respectively. The cross sectional area of the box-like construction shown in Figure 1 depends upon the particular size of heat exchange unit it is desired to produce and as will be observed from the aforesaid figure, the inner surfaces of the top, bottom, and end walls are provided or formed with alternate grooves and projections 15 and 16, respectively. The grooves in the top and bottom walls are arranged in alignment with the grooves in the end walls for receiving the marginal edge portions of suitable fins which are in the form of substantially flat plates 17. The grooves 15 are spaced transversely from each other a distance depending upon the space desired between the fins and are of such width as to slidably receive the fins.

In order to insure alignment of the grooves in the end walls with the grooves in the top

and bottom walls, the upper and lower edges of the former walls are provided with projections 18 arranged in registration with the grooves 15 in the inner surface thereof so as to slidably engage the grooves 15 in the top and bottom walls. In other words, the construction is such that when the projections 18, above described, are in engagement with the grooves 15 in the upper and lower walls, alignment of the grooves in the end walls 60 with the grooves aforesaid is insured. The top wall 11 of the box-like construction is preferably removable and is assembled with the box-like construction 10 after the fins have been properly positioned within the apparatus. One side wall of the box-like construction is provided with a plurality of slots 19 elongated transversely of the side wall and spaced from each other longitudinally of the wall a distance depending upon the desired 70 spacing of the water tubes 20. The opposite side wall is provided with projections 21 extending inwardly therefrom and spaced apart a predetermined distance for receiving therebetween the free ends of the water tubes after 75 the latter have been extended through pre-fashioned slots 22 in the fins.

In assembling the apparatus above described, the projections 18 on the lower edges of the end walls 13 are positioned within the 80 grooves 15 in the bottom wall so as to align the latter grooves with the grooves 15 in the end walls. After the end walls have been positioned as stated above, the latter are adjusted relative to each other to the proper distance apart and then the side walls are secured thereto in any suitable manner. The fins 17 are then assembled with the side and bottom walls in a manner to be more fully hereinafter described and after this is accomplished, one edge portion of the top wall 90 is placed upon the upper edge of one of the end walls with the projections 18 on the latter in engagement with the grooves 15 in the top wall. After this is accomplished, registration of the grooves 15 in the top wall with the upper marginal portions of the fins is insured when the top wall is slid in assembled position.

Referring now to the method employed for 100

assembling the fins and water tubes and with special reference to Figure 1, it will be noted that the fins are inserted from the top of the box by aligning the marginal end portions with opposite grooves 15 in the end walls 13 and sliding the fins downwardly until the lower marginal edge portions engage within the grooves 15 in the bottom wall. The top wall is then assembled with the box as previously stated and after this is accomplished, the water tubes 20 are extended through the slots 19 in one of the side walls and through the preformed apertures 22 in the fins. In this connection it is to be noted that the slots 19, above described, are open at their upper ends so that after removing the top wall 11, the fins and water tubes may be readily removed from the box-like construction as a unit. After the unit has been removed from the assembling apparatus, it may be dipped in a soldering solution to secure the fins to the tubes.

Thus, from the foregoing it will be observed that my improved method and apparatus is extremely simple and provides for readily and properly assembling the fins of the heat exchange unit upon the water tubes thereof.

What I claim as my invention is:

30 1. In apparatus for assembling heat exchange units of the fin and tube type, a box-like structure having end and bottom walls provided with alternate grooves and projections on the inner surfaces thereof with the 35 grooves in each of said walls arranged in registration, and a removable top wall having projections forming grooves in alignment with the grooves in the end walls and cooperating with the latter grooves and the 40 grooves in the bottom wall to receive the marginal edge portions of the fins.

45 2. In apparatus for assembling heat exchange units of the fin and tube type, a plate-like member having alternate grooves and projections on one surface thereof, a second plate-like member arranged at substantially right angles to the plate aforesaid and having grooves in the inner surface thereof registering with the grooves in said first-mentioned 50 plate for receiving adjacent marginal edges of the fins, and projections upon said second plate slidably engaging in the grooves in the first-mentioned plate for accurately positioning the second plate to insure alignment of the grooves in the latter with the 55 grooves in the first-mentioned plate.

60 3. In apparatus for assembling heat exchange units of the fin and tube type, a plate-like member having alternate grooves and projections on one surface thereof, a second plate-like member extending at substantially right angles to the plate-like member aforesaid and having grooves on the inner surface thereof registering with the grooves in the 65 first-mentioned plate for receiving adjacent

marginal edge portions of the fins, projections upon the edge of said second plate adjacent the first plate slidably engaging in the grooves in the latter plate for accurately positioning the latter and insuring alignment of 70 the grooves in said plates, and means cooperating with the plates aforesaid for embracing the remaining marginal edges of the fins.

4. In apparatus for assembling heat exchange units of the fin and tube type, a unit 75 having a bottom plate provided with alternate grooves and projections on the upper surface thereof, end plates arranged at substantially right angles to the bottom plate in spaced relation to each other and having 80 grooves in the inner surfaces thereof registering with the grooves in the upper surface of said bottom plate, a top plate-like member having grooves in the bottom surface thereof arranged in alignment with the 85 grooves aforesaid and cooperating with the latter to receive the marginal edge portions of the fins, and means upon the end plates for accurately positioning the top plate relative thereto.

5. In apparatus for assembling heat exchange units of the fin and tube type, a unit 90 having spaced walls provided with alternate grooves and projections on the inner surfaces thereof with the grooves opposite each other, 95 a wall connecting the walls aforesaid and having grooves on one surface thereof registering with the grooves in the end walls, and cooperating interengaging means upon the end walls and connecting wall for accurately 100 positioning the said walls to insure alignment of the grooves.

6. In apparatus for assembling heat exchange units of the fin and tube type, a unit 105 having spaced walls provided with grooves and projections on the inner surfaces thereof with the grooves arranged opposite each other, a connecting wall having grooves on one surface thereof arranged in registration with the grooves in the walls aforesaid, and projections upon the latter walls intermediate the grooves therein for slidably engaging the grooves in the connecting wall to insure alignment of the latter grooves with the grooves 110 in the other walls.

7. In apparatus for assembling heat exchange units of the fin and tube type, a box-like structure having top, bottom and end walls provided with grooves on the inner surfaces thereof cooperating to receive the marginal edges of a plurality of fins, and a side wall for said structure slotted for receiving the tubes to permit the passage of the same through the fins.

8. In apparatus for assembling heat exchange units of the fin and tube type, a box-like structure having end and bottom walls provided with alternate grooves and projections on the inner surfaces thereof with the 125 grooves arranged in registration, a removable 130

top wall having grooves on the inner surface thereof cooperating with the grooves in the walls aforesaid to receive the marginal edges of a plurality of fins, and means for guiding the top wall in assembled relation with the walls aforesaid to insure registration of the grooves therein with the adjacent marginal edge portions of the fins.

9. In apparatus for assembling heat exchange units of the fin and tube type, a pair of spaced walls having alternate grooves and projections on the inner surfaces thereof with the grooves arranged opposite each other for receiving opposite ends of a plurality of fins, a removable connecting wall having grooves therein arranged to register with the grooves in the walls aforesaid and adapted for positioning upon the spaced walls after the fins have been assembled with the latter, and means for guiding said connecting wall into operative relation with the fins.

10. In apparatus for assembling heat exchange units of the fin and tube type, a pair of spaced walls having alternate grooves and projections on the inner surfaces thereof with the grooves arranged opposite each other for receiving opposite ends of a plurality of fins, a removable connecting wall having grooves therein arranged to register with the grooves in the walls aforesaid and adapted for positioning upon the spaced walls after the fins have been assembled therewith, and projections upon said spaced walls intermediate the grooves therein for slidably engaging the grooves in the top wall upon assembling the latter for accurately registering the grooves therein with the fins.

11. In apparatus for assembling heat exchange units of the fin and tube type, a pair of spaced walls having alternate grooves and projections on the inner surfaces thereof with the grooves arranged opposite each other for receiving opposite ends of a plurality of fins, a removable connecting wall having grooves therein arranged to register with the grooves in the walls aforesaid and adapted for positioning upon the spaced walls after the fins have been assembled therewith, and means for guiding the connecting wall in assembled relation with the walls aforesaid and in registration with the adjacent marginal edges of the fins including means upon the transverse edge portions of the spaced walls adjacent the connecting wall arranged to slidably engage cooperating means on the connecting wall.

12. In apparatus for assembling heat exchange units of the fin and tube type, a pair of spaced walls having alternate grooves and projections on the inner surfaces thereof with the grooves arranged opposite each other and having projections intermediate the grooves on the opposite transverse edges thereof, and connecting walls having grooves therein registering with the grooves in the walls

aforesaid and slidably engaging said projections for insuring alignment of the grooves.

13. In apparatus for assembling heat exchange units of the fin and tube type, a box-like structure comprising, end walls having grooves in the inner surfaces thereof arranged opposite each other and having projections intermediate the grooves extending from the transverse edge of said walls, top and bottom walls having grooves in the inner surfaces thereof registering with the grooves aforesaid and slidably engaging the projections for insuring alignment of the grooves, and side walls secured to the end walls, one of said side walls having open-ended slots therein for receiving the tubes to permit the latter to be passed through the fins.

14. In apparatus for assembling heat exchange units of the fin and tube type, a pair of oppositely arranged walls having alternate grooves and projections on the inner surfaces thereof with the grooves arranged opposite each other for receiving the marginal edges of a plurality of fins, a side wall secured to the end walls and having slots therein spaced a predetermined distance apart for receiving a plurality of tubes to permit the latter to be passed through the fins.

15. In apparatus for assembling heat exchange units of the fin and tube type, a unit having means engageable with each of the marginal edge portions of a plurality of fins to support the latter in predetermined spaced relation and fashioned to permit a plurality of tubes to be extended through the fins while the latter are supported by said means.

16. Apparatus for assembling heat exchange units of the fin and tube type, comprising a plate-like member having a plurality of spaced grooves therein for receiving one of the marginal edges of a plurality of fins, a second removable plate-like member having grooves therein corresponding to the grooves aforesaid for receiving the opposite marginal edges of each of the fins, and means for accurately positioning said removable plate-like member relative to the other member upon moving the former in assembled relation with the latter to insure registration of the grooves in said removable plate with the adjacent marginal edges of the fins.

17. Apparatus for assembling heat exchange units of the fin and tube type, comprising a box-like structure having top, bottom and end walls, each provided with registering grooves on the inner surfaces thereof for receiving the marginal edges of a plurality of fins.

18. Apparatus for assembling heat exchange units of the fin and tube type wherein the fins are provided with openings therethrough for receiving the tubes, comprising a unit having means engageable with the top, bottom and end marginal edges of each of a plurality of fins to support the latter in

predetermined spaced relation and to insure alignment of the openings therein.

19. Apparatus for assembling heat exchange units of the fin and tube type, comprising a box-like structure having bottom and end walls and having a removable top wall, each formed with grooves on the inner surfaces thereof cooperating to receive the marginal edges of a plurality of fins, and
- 5 means for guiding said removable wall in assembled relation with the box-like structure to insure registration of the grooves therein with the adjacent marginal edges of the fins.
- 10 20. Those steps in the method of manufacturing heat exchange units of the fin and tube type which consist in engaging opposite and adjacent marginal edges of each of a plurality of fins for supporting the latter
- 15 20 in spaced relation to each other and extending tubes through prefashioned openings in the fins while the latter are so supported.

In testimony whereof I affix my signature.
WILLIAM C. RITTER.
